REFRIGERATOR EVAPORATOR

Si J. Williams, Jr., Evansville, Ind., assignor to International Harvester Company, a corporation of New Jersey

Application December 11, 1952, Serial No. 325,323

2 Claims. (Cl. 62—126)

This invention relates generally to refrigerator evaporators and more specifically to improved refrigerator evaporators which when mounted in a refrigerator will efficiently and effectively function during both the refrigeration cycle and the defrost cycle of the refrigerator.

It is an object of this invention to provide an evaporator which will function to efficiently refrigerate a compartment of a refrigerator and which may be efficiently defrosted to melt accumulations of frost which will effectively and rapidly drain from the surfaces of the evaporator.

It is another object of this invention to provide an evaporator in a refrigerator which will efficiently refrigerate different portions of a refrigerator compartment to different degrees.

It is a feature of this invention that a length of serpentine tubing cooperates with a header connected to a plurality of parallel tubes to form a portion of a refrigerator evaporator.

It is another feature of this invention that two lengths of capillary tubing are used to provide different ranges of temperature in a refrigerator evaporator.

Other objects and features of the invention will be apparent upon a perusal of the following specification and drawings, of which:

Figure 1 is a partial front plan view of a refrigerator cabinet embodying the invention;

Figure 2 is a side plan view of the evaporator shown in Figure 1;

Figure 3 is a top sectional view of the refrigerator cabinet shown in Figure 1 embodying the invention;

Figure 4 is a top sectional view of a refrigerator cabinet showing another embodiment of the invention; and

Figure 5 is a side plan view of the evaporator shown in Figure 4.

The present embodiments are the preferred embodiments but it is to be understood that changes can be made in the present embodiments by one skilled in the art without departing from the spirit and scope of this invention.

It is advantageous that a refrigerator evaporator be so constructed as to provide a maximum usable volume within the confines of the refrigerator low temperature compartment for the storage of food. It is further advantageous to provide a refrigerator evaporator which will refrigerate certain portions of the refrigerator evaporator to one degree and will refrigerate other portions of the refrigerator evaporator to other degrees. It is further advantageous to provide a refrigerator evaporator which may be rapidly defrosted, which will not permit puddles of water to accumulate within the confines of the evaporator, and which will not permit defrost water to drain onto any food disposed within the confines of the evaporator. This invention incorporates all of these advantages.

To describe the invention in detail, reference is first made to Figures 1-3. Part of a refrigerator cabinet 30 is shown in which a compartment 32 is defined by the inner liner 52. A refrigerator door 31 is pivotally mounted to the refrigerator cabinet 30 as can easily be seen in Fig-

2

ure 3. The compartment 32 is divided by a tray 33. The tray 33 serves to collect the defrost water dripping from the evaporator and also serves to define a freezer compartment in the upper portion of the refrigerator cabinet, as can easily be seen in Figure 1. The evaporator comprises a vertical rear wall portion 34 and a horizontal base 35. The rear wall portion 34 and the base 35 are disposed at right angles to each other and are maintained in this position by the pair of diagonal braces 36. The vertical rear portion 34 is positioned substantially adjacent to the rear wall of the inner liner 52, and the base 35 is positioned substantially adjacent to the upper side of the tray 33. Thus it may be seen that a maximum amount of the space within the inner liner 52 above the tray 33 is usable for the storage of food.

The rear wall portion 34 of the evaporator comprises an upper header 37, a lower header 38, and a plurality of parallel tubes 39. The parallel tubes 39 interconnect the upper header 37 and the lower header 38, as can easily be seen in Figure 1. To the upper portion of the upper header 37 an outlet or suction tube 40 is connected.

The base 35 comprises a length of serpentine tubing 43, as can easily be seen in Figure 3. The serpentine tubing 43 has a number of straight parallel sections which are disposed in a horizontal plane and which are perpendicular to the longitudinal axis of the lower header 38. The ends of the straight sections of the serpentine tubing 43 are interconnected by curved sections. One end of the serpentine tubing 43 is formed to a reduced diameter to connect with a capillary tube 44. The other end of the serpentine tubing 43 is extended and connected to the lower header 38 at the junction 41. A plurality of rods or wires 45 are mounted to the upper surface of the serpentine tubing 43, as can easily be seen in Figures 2 and 3. The rods 45 are disposed parallel to one another and are also parallel to the longitudinal axis of the lower header 38. The rods 45 are mounted in thermal contact with the serpentine tubing 43.

It is intended that the capillary tube 44 be connected to the outlet side of a conventional refrigerator condenser (not shown), and it is further intended that the outlet tube 40 be connected to the inlet side of a conventional refrigerator compressor (not shown), thereby liquid refrigerant will be supplied to the evaporator through the capillary 44 and refrigerant gases will be withdrawn from the evaporator through the outlet tube 40. It may then be seen that liquid refrigerant will flow through the length of serpentine tubing, through the lower header 38, through the parallel tubes 39 to the upper header 37. As heat from any food placed within the confines of the evaporator is conducted to the rods 45, and in turn conducted to the serpentine tubing 43, and in turn conducted to the liquid refrigerant disposed therein, the liquid refrigerant will be heated to its latent heat of vaporization, at which point it will assume a gaseous state and will flow through the serpentine tubing 43 into the lower header 38 and through the remainder of the rear wall portion 34 to the outlet tube 40. Any food placed within the confines of the evaporator adjacent to the rear wall 34 will also conduct heat to the parallel tubes 39 of the rear wall portion 34 to cause the liquid refrigerant disposed therein to assume a gaseous state, which gases will also be easily withdrawn from the evaporator through the outlet tube 40. The serpentine tubing 43 and the rods 45 of the base 35 provides efficient means for conducting heat from any food placed upon the base 35, while the specific construction of the rear wall 34 provides means for conducting heat from any food placed adjacent thereto and for conducting the gases formed in the base 35 of the evaporator. Thus it can be seen that any food placed within the confines of the evaporator will be efficiently cooled. Now, when

the evaporator has accumulated a certain amount of frost upon the surfaces thereof, and is defrosted by any conventional method, the accumulated frost will be melted and the water thereby formed will drip from the rear wall portion 34 and the base 35. The defrost water will drip into the tray 33 and may be removed therefrom by any conventional method (not shown). No puddles will accumulate upon the base 35 due to the specific structure of the base 35, as the water will drip between the rods 45, and also will easily drip from the serpentine tubing 43. The defrost water from the rear wall portion 34 will flow downward along the parallel tubes 39 to the lower header 38, and will drip from the lower header 38 into the tray 33. It may then be easily seen that no defrost water will drip upon any food disposed within the freezer compartment. Further, because any food disposed within the freezer compartment will be positioned upon the rods 45 a minimum amount of defrosting of any frozen food placed thereon will result.

To describe the embodiment shown in Figures 4 and 5, reference is made thereto. This embodiment is identical to the embodiment shown in Figures 1 through 3 except for the inlet and outlet tubes of the base 35 and the rear wall portion 34. The various parts of the embodiment shown in Figures 4 and 5 are numbered with the same numbers used in Figures 1 through 3 where these parts have functions identical to the functions described above for those identically numbered parts. One end of the serpentine tubing 43 is extended to form an outlet tube 54. The other end of the serpentine tubing 43 is connected to a length of capillary tubing 51 or tubing 51 of a substantially reduced diameter. The other end of the capillary tubing 51 is connected to the lower header 38. A second length of capillary tubing 50 is connected to the upper surface of the upper header 37 to form an inlet tube. It is intended that the capillary tubing 50 be connected to the outlet side of a conventional refrigerator condenser (not shown), and that the outlet tube 54 be connected to the inlet side of a conventional refrigerator compressor (not shown). It may then be seen that liquid refrigerant will enter the capillary tube 50, will flow into the upper header 37, will flow through the various parallel tubes 39 into the lower header 38, will flow through the capillary tubing 51 into the serpentine tubing 43. This will result in a substantially greater difference in pressure between the ends of the serpentine tubing 43 as compared to the inlet and outlet of the rear wall portion 34. Thus the liquid refrigerant will evaporate more rapidly in the base 35 than in the rear wall portion 34 and, consequently, the base 35 will have a greater cooling effect upon any food positioned thereon, than the cooling effect upon any food placed adjacent to the rear wall portion 34. Due to the construction of the rear wall portion 34, sufficient area is provided for an effective refrigeration of any food placed adjacent to the rear wall portion 34. It may then be easily seen that the afore-described construction provides an evaporator which will efficiently serve to cool any food placed within the freezer compartment.

This evaporator may be defrosted in any conventional manner, and as previously described due to the construction of the base 35 and the rear wall portion 34, the defrost water will be effectively drained from the evaporator into the tray 33 without the formation of puddles of water within the confines of the evaporator, and without the dripping of any defrost water upon any food placed within the confines of the evaporator. Also, since the base 35 provides a greater cooling effect than the rear wall portion 34, more frost will accumulate upon

the surface of the base 35 than will accumulate upon the rear wall portion 34. Because of the specific construction of the base 35, as described above, this additional frost will be efficiently removed from the base 35 when the evaporator is defrosted.

Having described the invention, what is considered new and desired to be protected by Letters Patent is:

1. An evaporator for a refrigerator comprising a horizontally disposed base portion and a vertically disposed rear wall portion, said rear wall portion comprising an upper and a lower header and a plurality of parallel tubes interconnecting said headers, said base portion comprising a length of serpentine tubing having straight parallel sections interconnected by curved sections, said straight sections positioned in a horizontal plane including said lower header, said straight sections further positioned perpendicular to the longitudinal axis of said lower header, a plurality of rods mounted in a parallel spaced apart relationship to each other and to the longitudinal axis 10 of said lower header on the upper surface of said serpentine tubing in thermal contact therewith, a pair of diagonal braces, each one of said braces mounted from one end of said rear wall portion to one end of said base portion, a length of capillary tubing connected between 15 one end of said serpentine tubing and said lower header, a second length of capillary tubing connected to the upper surface of the upper header, whereby said second length of capillary tubing serves as an inlet tube for liquid refrigerant, and whereby the other end of said serpentine tubing forms an outlet tube.

2. In a refrigerator, an inner liner within said refrigerator, a horizontally disposed tray mounted in cooperation with said inner liner to thereby form a compartment positioned within said inner liner above said tray, evaporator means disposed within said compartment for refrigeration of said compartment comprising a horizontally disposed base portion and a vertically disposed rear wall portion, said base portion having a horizontal area substantially equal to the horizontal area of said tray, said rear wall portion having a vertical area substantially equal to the area of the rear portion of said inner liner above said tray, said rear wall portion comprising an upper and a lower header and a plurality of parallel tubes interconnecting said headers, said base portion comprising a length of serpentine tubing having straight parallel sections interconnected by curved sections, said straight sections positioned in a horizontal plane including said lower header, said straight sections further positioned perpendicular to the longitudinal axis of said lower header, a plurality of rods mounted in a parallel spaced apart relationship to each other and to the longitudinal axis of said lower header on the upper surface of said serpentine tubing in thermal contact therewith, a length of capillary tubing connected between one end 35 of said serpentine tubing and said lower header, a second length of capillary tubing connected to the upper surface of the upper header, whereby said second length of capillary tubing serves as an inlet tube for liquid refrigerant, and whereby the other end of said serpentine tubing 40 forms an outlet tube.
